Filed Nov. 14, 1956, Ser. No. 622,060

3 Claims. (Cl. 137—793)

This invention relates generally to pressure responsive actuator elements and particularly to assemblies of this type having a relatively linear correlation of pressure, or loading, and deflection.

As is well known, actuator elements of the type herein disclosed are used extensively for actuation of switches or other control apparatus which have application in the regulation of pressure and temperature in the refrigeration and allied fields. One problem existing in this and similar applications is that in the upper portion of the deflection range of the actuator element, the deflection of the flexible member for a given incremental change in internal pressure tends to decrease due to the inherent stiffness of the material from which the flexible member is formed and because of the inherent spring rate of the lever system or switch assembly which the actuator element must operate.

The present invention solves this difficulty by forming a corrugation in the flexible member which is so shaped, in profile, that increasing pressure within the actuator element, tending to spread apart the side walls of the corrugation, increases incrementally the force transmitted to the actuator thrust pin for the upper portion of the element's deflection range.

An object of the present invention is to provide an actuator element having a relatively uniform deflection rate over a wide range of loading.

A further object is to provide an actuator element of relatively small size which is reinforced so as to be safely operable under relatively large loading.

A further object is to provide a flexible element or diaphragm for a pressure responsive actuator which is formed so as to provide, when assembled into an actuator, a relatively linear pressure-temperature deflection characteristic.

These and other objects will become apparent as the description proceeds with reference to the accompanying drawings in which:

Figure 1 represents a cross-sectional view of an actuator assembly embodying the present invention.

Figure 2 is a schematic view illustrating, in exaggerated form, the locus of certain points on the diaphragm corrugation.

Figure 3 is a top view of the actuator housing with the other parts of the assembly removed.

Referring initially to Figure 1, there is shown generally at 10 a cup-shaped housing having a bottom wall 11 and a cylindrical threaded side wall 12. A capillary tube 13 is soldered or otherwise rigidly secured within a central passage 14 in the wall 11. Overlying wall 11 is a flexible element or diaphragm 16 having a corrugation 17 adjacent its outer margin, the corrugation having an outer wall 17a spaced radially outward from its inner wall 17b. The point of maximum curvature of the outer wall or the corrugation 17 is indicated at 18. The point of maximum curvature of the inner wall of the corrugation is indicated at 19. Serving to clamp and seal the marginal edge of the diaphragm 16 against the wall 11

2

is an annular ring 21 having grooves at 22 in its lower face to provide for cold flowing of the material from which the diaphragm 16 is formed as the ring 21 presses the diaphragm into sealing engagement with the wall 11.

5 It will be understood that the diaphragm 16 may be formed of any suitable flexible material which can be given the required shape to establish the corrugation 17, beryllium-copper being particularly suited for this application. Threaded into the housing 10 is a clamping member 23 which is adapted to be tightened against ring 21 to thereby provide the force required to seal the diaphragm 16 against the wall 11.

A thrust pin 24 extends freely through an opening in the clamping member 23 and has a disc-shaped portion 15 26 which overlies the area of the diaphragm 16 within the corrugation 17. It will be understood that thrust pin 24 is adapted to actuate, through an appropriate lever assembly (not shown), a switch or other control means. As may best be seen in Figure 3 the upper face of the lower wall 11 has radial grooves 27 therein which extend within the area of bottom wall 11 which underlies the corrugation 17. Presence of grooves 27 insure that the fluid fill has entry into the chamber formed by diaphragm 16 and wall 11 even though the central portion 25 of the diaphragm 16 should be in near contact with the wall 11.

It will be understood that the pressure chamber formed by the wall 11 and the diaphragm 16 is adapted to be filled by a pressure transmitting fluid through the capillary tube 13. The remote end of the tube 13 (not shown) may be joined to a temperature sensing bulb, the capillary and pressure chamber serving to extend the diaphragm outwardly in a manner well known in the art. It will be further understood that the pressure chamber may respond to remote pressure changes, rather than temperature changes at the bulb, such pressure changes being transmitted to the chamber by means of a pressure transmitting fluid in the capillary, as, well known in the art. As shown in Figure 1, the diaphragm 30 17 is in a partially extended position indicating that the pressure within the chamber formed by the diaphragm 16 and the wall 11 is at an intermediate value. As the pressure within the chamber increases further to cause the pin 24 to move outwardly, the outer side wall of

45 the diaphragm corrugation 17 will tend to bulge outwardly slightly. The force (the direction of which is shown at 28 in Figure 3) producing this slight distortion will correspondingly tend to move point 18 downwardly and, because of the resulting flattening of the top of the corrugation, will move point 19 upwardly. The force produced by this tendency to move point 19 upwardly is additive to the force of the fluid pressure exerted on the underside of the central portion of the diaphragm 16 which drives the pin 24 in an upward direction. The 50 added incremental upward force provided by the action of the corrugation 17 tends to compensate for the added force required to overcome the increasing spring rate of the mechanism actuated by the pin 24 and tends to compensate for the spring rate, or increasing stiffness, of the diaphragm material as the actuator approaches its 55 fully extended position. Because of the reinforcement against bursting failure provided by the portion 26 of pin 24 overlying the marginal portion of the area of the diaphragm, the actuator assembly may be made relatively small and yet safely operate within a relatively high pressure range.

60 It will be understood that the invention herein described may be modified over that disclosed; the invention is to be limited only as defined in the following 65 claims:

1. A disc-shaped diaphragm adapted to be sealed across the open end of a cup-shaped housing to form a pres-

sure chamber and adapted to flex outwardly from an unextended position in response to an increase in the pressure within the pressure chamber, said diaphragm having an annular corrugation formed therein, said corrugation having an outer wall generally normal to the plane of the diaphragm, said corrugation having a cross-sectional configuration such that a transverse line joining the point of maximum curvature of the outer margin of said corrugation and the point of maximum curvature of the inner margin thereof forms an acute angle with the plane of said diaphragm when said diaphragm is in said unextended position, sideward flexure of said outer corrugation wall under increased pressure within said chamber thereby generating a force which tends to compensate for the increased force-deflection ratio of said diaphragm at the upper limit of its deflection range. 15

2. A diaphragm as claimed in claim 1 which is formed of beryllium-copper.

3. A disc-shaped diaphragm adapted to be supported at its circumference and to flex in one direction in response to an increase in pressure on one of its faces, said diaphragm having an annular corrugation formed therein with said one diaphragm face defining the con- 20

cave portion of said corrugation, the outer walls of said corrugation being generally normal to the plane of said diaphragm, said corrugation having a cross-sectional configuration such that a transverse line joining the point of maximum curvature of the outer margin of said corrugation and the point of maximum curvature of the inner margin thereof forms an acute angle with the plane of said diaphragm when said diaphragm is unflexed, sideward flexure of said outer corrugation wall under increased pressure on said one face of said diaphragm thereby generating a force which tends to compensate for the increased force-deflection ratio of said diaphragm at the upper limit of its deflection range.
